[57] CLAIM

The ornamental design for sunglasses, substantially as shown and described.

DESCRIPTION

FIG. 1 is a front elevational view of sunglasses showing my new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

The sunglasses are characterized by a series of tapered conical projections disposed along the length of the curved top portion of each frame, the conical projections all being identical to one another and the conical projections of each frame being equally and uniformly spaced from adjacent projections.
